FIRE EXTINGUISHER HOUSING

Lawton M. Dial, Jr., and Louis J. Grossheim, Houston, Tex., Donald M. Schramme, Baton Rouge, La., and Walter H. Zennecker, Houston, Tex., assignors to Arthur Dooley and Son, Inc., Beaumont, Tex.

Filed Feb. 12, 1970, Ser. No. 21,411

Term of patent 14 years

Int. Cl. D29—01

U.S. Cl. D16—2

FIG. 1

FIG. 2

FIG. 3

FIG. 4

FIG. 1 is a front perspective view of a fire extinguisher housing embodying our design;

FIG. 2 is a side elevation thereof;

FIG. 3 is a top plan view thereof; and,

FIG. 4 is a front perspective view of a modified embodiment of the housing illustrated in FIG. 1.

The broken lines are shown for illustrative purposes only and form no part of the claimed design.

We claim:

The ornamental design for fire extinguisher housing, substantially as shown and described.
